RACK

Harry H. Fante, Detroit, Mich., assignor to L. A. Young Spring & Wire Corporation, Detroit, Mich.

Application March 20, 1933. Serial No. 661,854

4 Claims. (Cl. 211—181)

The main objects of this invention are:

First, to provide an improved rack of wire or light rod for conical molds or cups of the type used in freezing and molding and handling ice cream and the like.

Second, to provide a rack having the above desirable characteristics and uses and which is light in weight, provides for a maximum circulation of the freezing medium about the walls of the containers and exposes practically the whole exterior of the container to the freezing medium, and which is structurally strong and highly efficient for the purpose intended.

Objects relating to details and economies of my invention will appear from the description to follow. The invention is defined and pointed out in the claims.

A structure which is a preferred embodiment of my invention is illustrated in the accompanying drawing, in which:

Fig. 1 is a perspective view of a rack embodying the features of my invention.

Fig. 2 is an enlarged fragmentary longitudinal section on a line corresponding to line 2—2 of Fig. 1.

Fig. 3 is an enlarged fragmentary transverse section on a line corresponding to line 3—3 of Fig. 1.

Fig. 4 is an enlarged fragmentary top plan view.

Fig. 5 is an enlarged fragmentary detail section on a line corresponding to line 5—5 of Fig. 4.

Fig. 6 is a fragmentary view in side elevation of a plurality of the racks arranged in stacked relation.

Referring to the embodiment of my invention illustrated in the drawing, 1 represents the top frame, 2 the intermediate frame, and 3 the bottom frame. The frames are substantially rectangular and are arranged in spaced parallel relation, the intermediate frame being spaced only a short distance below the top frame.

Spaced uprights 4, and hairpin-like corner uprights 5, connect the frames in assembled relation. The bights 6 of the hairpin-like corner uprights project above the top frame to form stacking lugs for maintaining a stack of the racks in vertical alignment.

The top and intermediate frames are provided with coacting cup holders 8 and 9, respectively, made up of pairs of transverse wires 10, 10 bowed or looped in opposed relation at 11 and longitudinal wires 12 disposed in crossing relation at 13 between the loops with the parts weld-

ed together. The cup holders 8 are of larger diameter than the cup holders 9 so that they are adapted to receive the conical molds or cups 14 of the type used to contain ice cream and the like. The frames, uprights, and holders are made of light rod or heavy gauge wire and are secured in assembled relation by means of welding. Fig. 5 illustrates the welded joints. The top and bottom frames are preferably formed of substantially heavier stock than the remaining parts of the rack.

With the parts thus arranged, the conical cups 14 which are preferably of paper are inserted in the loop-like holders of the rack, filled with ice cream mixture, and the entire rack is then placed in a freezing medium to solidify the mixture in the conical cups. The open wire formation of the rack and holders provides for a maximum circulation of the freezing medium about the containers or cups and exposes practically the entire exterior of each container to the freezing medium. Thus, the rack is highly efficient for use in freezing ice cream mixture in the conical containers or molds. The rack, of course, may be used in other relations—for example, in the serving of the cones or cups filled with liquid.

My improved rack is structurally strong and highly efficient for the purpose intended, yet in weight it is comparatively light. A plurality of the trays may be stacked in vertical alignment, as illustrated in Fig. 6, in the refrigerator or when the trays are not in use.

I have illustrated and described my improvements in an embodiment which I have found very practical. I have not attempted to illustrate or describe other embodiments or adaptations, as it is believed this disclosure will enable those skilled in the art to embody or adapt my improvements as may be desired.

Having thus described my invention, what I claim as new and desire to secure by Letters Patent is:

1. A rack of wire or light rod comprising in combination, spaced parallel substantially rectangular top, intermediate and bottom frames, spaced uprights disposed on the inner sides of said frames, holders for conical cups on said top and intermediate frames and consisting of coacting pairs of transverse members looped or bowed in opposed relation and longitudinal members disposed in crossing relation between the loops, and means uniting the parts in assembled relation.

2. A rack comprising vertically spaced frame

members, vertically aligned coacting pairs of holder members connected at their ends to opposite sides of the frame members, the holder members of coacting pairs having opposed semi-circular loops providing annular holders, the lower holders being of less diameter than the upper, the reaches of said holder members between said loops being disposed in straight side by side contacting relation and secured together.

5. A rack comprising vertically spaced frame members, vertically aligned coacting pairs of holder members connected at their ends to the frame members, the holder members of coacting pairs having opposed loops providing holders, the lower holders being of less diameter than the upper, and tie members disposed across the reaches of said holder members and secured thereto and at their ends to opposed sides of the frame.

3. A rack comprising vertically spaced frame members, and vertically aligned coacting pairs of holder members connected at their ends to opposite sides of the frame members, the holder members of coacting pairs having opposed semi-

circular loops providing annular holders, the lower holders being of less diameter than the upper, the reaches of said holder members between said loops being disposed in straight side by side contacting relation and secured together.

4. A rack comprising vertically spaced frame members, vertically aligned coacting pairs of holder members connected at their ends to the frame members, the holder members of coacting pairs having opposed loops providing holders, the lower holders being of less diameter than the upper, and tie members disposed across the reaches of said holder members and secured thereto and at their ends to opposed sides of the frame.

HARRY H. FANTE.
